TERMINAL CRIMPING TOOL

Charles W. Candiotti, Garden City, N.Y., and Clemence N. Butts, Bluffton, Ind., assignors to Car-Venience Parts Manufacturing, Inc., Bluffton, Ind., a corporation of Indiana

Filed Feb. 3, 1965, Ser. No. 430,380
9 Claims. (C. 72—412)

The present invention relates to a terminal crimping tool, and more particularly to a hand tool by which conventional solderless terminals can be conductively secured to conductors with relative ease.

The primary purpose of this invention is to provide a simple and relatively inexpensive hand tool by which conventional solderless terminals, of varying sizes, can be crimped and thereby secured to conductors with relative ease.

Another object of this invention is to provide an improved terminal crimping hand tool by which terminals varying from 10 gauge to 22 gauge can be crimped in a manner permanently insuring a conductive contact between the conductor and the terminal to which it is secured.

Still another object of this invention is to provide an improved terminal crimping hand tool which is easy to use and inexpensive to manufacture.

A further object of this invention is to provide a hand tool comprising two parts which are identical, and therefore, interchangeable, by which conventional solderless terminals can be crimped in a manner insuring a permanent conductive contact between the terminal and the conductor to which it is secured.

Still further an object of this invention is to provide an improved terminal crimping hand tool having a gauge thereon which indicates the proper distance a conductor should be stripped for the attachment of a conventional terminal.

The above-mentioned and other features and objects of this invention and the manner of attaining them will become more apparent and the invention itself will be best understood by reference to the following description of an embodiment of the invention taken in conjunction with the accompanying drawings, wherein:

FIG. 1 is a plan view of one of the identical parts comprising the improved tool of this invention;

FIG. 2 is a side edge view of the part illustrated in FIG. 1;

FIG. 3 is a fragmentary and cross-sectional view of both parts of the tool of this invention, illustrating one of the parts secured to a piece of soft wood and the other part of the tool placed in operating relation thereto and with a conventional solderless terminal positioned between the two parts in the position that a terminal can be crimped to permanently and conductively secure the terminal to a conductor; and

FIG. 4 is a fragmentary plan view of the block of wood, illustrated in FIG. 3, with one part of the tool of this invention secured thereto, illustrating the use of the wire-stripping gauge thereon.

In the broader aspects of this invention there is provided a pair of identical plates having a pair of spaced-apart openings therein, a means for securing the plates to a support, and adjacent one of the ends of the plates a pair of leg portions with an edge extending therebetween.

The leg portions of either one of the plates are adapted to fit into the openings of the other of the plates and means are provided by which the two plates can be forc-

2

ibly urged together thereby to crimp terminals between the edge of the one plate and the surface of the other plate.

Referring to the drawings, there is illustrated an improved terminal crimping hand tool generally comprising two identical parts which are generally indicated by the reference numerals 10. Each of the parts 10 is made of sheet material, preferably metal, which will retain its shape during the use of the tool as will be later described. Preferably, both parts 10 of the tool are made from 12-gauge cold rolled steel sheet; however, other materials having similar properties would also be satisfactory. Both parts 10 comprise a sheet of material generally rectangular in shape having longitudinal, straight and parallel edges 12, 14 and opposite, lateral, straight and parallel end edges 16, 18 which are perpendicular to edges 12, 14.

Edges 12, 14 are parallel to a longitudinal axis 20 on which two rectangularly shaped openings 22, 24 are positioned. Openings 22, 24 are identical in size and are positioned coaxially with the part 10 and in end-to-end and spaced-apart relationship. Adjacent opposite corners of the part 10 are positioned a second pair of openings 26, 28, which are circular in shape and which are used for securing one of the parts 10 to a support as will be described hereinafter.

Communicating with edge 18 is a notch 30 which is defined by opposite edges 32, 34 of part 10 which are parallel to each other and parallel to longitudinal edges 12, 14, and an edge 36 of part 10 extending between edges 32, 34. Edge 36 is curved about a center of curvature located on the axis 20. Edges 32, 34 and edges 12, 14 define parallel leg portions 40, 42. At end edge 16 there is provided an anvil surface 44 which is used to receive a force 46, indicated by the arrow illustrated in FIG. 3, which will be described hereinafter.

Openings 22, 24 have dimensions slightly larger than leg portions 40, 42 and are spaced-apart generally a distance corresponding to the distance between leg portions 40, 42, thereby being adapted to receive leg portions therein as illustrated in FIG. 3.

Each part 10, as described, also has two oppositely facing flat surfaces 47, 48 on one of which there is placed indicia 50 comprising a line extending longitudinally of the part 10 and parallel to the axis 20 and edges 12, 14. As illustrated, indicia 50 is closer to edge 14 than edge 12; however, the indicia 50 could be placed on surfaces 47, 48 so that the opposite would be true. Indicia 50, in both cases, is positioned a distance "A" away from its closest edge, edge 14 as illustrated in FIG. 1, corresponding to the length of bare wire needed to properly attach a terminal to a conductor.

The specific embodiment illustrated is an embodiment of the tool of this invention designed to be used on terminals ranging in size from 10 to 22 gauge. It will be obvious that the tool of this invention can be made in different sizes for other size terminals. In the drawings, the figures are made to scale and the specific embodiment illustrated preferably has the following dimensions. Plate 10 measures one and seven-eighths inches in length, seven-eighths inch in width, has a thickness equal to the thickness of 12-gauge cold rolled steel of approximately 0.017 inch. Leg portions 40, 42 have a rectangular cross-section measuring one-quarter inch in length and a width equal to the thickness of 12-gauge cold rolled steel. Leg portions 40, 42 are spaced-apart a distance of three-eighths inch measured perpendicularly between edges 32, 34. Edge 36 has a radius of five-eighths inch and a center of curvature on axis 20 one-eighth inch from end 18 measured toward openings 22, 24. Openings 22, 24, as

above-mentioned, have dimensions slightly larger than leg portions 40, 42, and are spaced-apart so that leg portions 40, 42 can be inserted therein. In a specific embodiment the dimensions of openings 22, 24 are 0.265 inch in length, 0.02 inch in width, and are spaced-apart a distance measured from adjacent ends of openings 22, 24 of 0.365 inch. Lastly, indicia 50, in the embodiment illustrated, is spaced from edge 14 a distance of one-quarter inch.

In operation, referring to FIGS. 3 and 4, one of the parts 10, given a reference numeral 10a for identification, is secured to the surface of a piece of wood 52 by means of a pair of screws 54, 56 inserted through the respective openings 26, 28. Mounted in this manner, indicia 50 faces upwardly and can be utilized to gauge the correct length of bare wire needed to secure a terminal to a conductor as shown in FIG. 4. To prepare a conductor 58 for the attachment of a terminal, conductor 58 is laid perpendicular to edge 14 of part 10a and stripped of insulation from the end thereof a distance corresponding to the distance "A" between the indicia 50 and the edge 14 thereby exposing that length of bare wire 60. Conductor 58 is then positioned intermediate openings 22, 24 with its bare wire 60 inserted into the gripping portion 64 of a conventional solderless terminal 62, as shown in FIG. 4. Then the other part 10, given the reference numeral 10b for identification, is placed in the position illustrated in FIG. 3 in which the leg portions 40, 42 are inserted into the openings 22, 24 of part 10a and the part 10b is generally perpendicular to the part 10a. In this position, the gripping portion 64 of the terminal 62 is positioned directly between the openings 22, 24 of part 10a and is surrounded by the edges 32, 36, 34 of part 10a and one of the surfaces 47, 48 of part 10a which faces surface 36 of part 10b. With the parts 10a, 10b of the tool of this invention thus positioned, the gripping portion 64 of the terminal 62 is crimped and permanently attached to conductor 58 in a manner insuring a permanent conductive contact between the bare wire portion 60 and the terminal 62 by means of supplying a force, diagrammatically indicated by the arrow 46, to the anvil surface 44 at end 16 thereby urging the part 10b toward the part 10a and the edge 36 toward the respective surface 47 or 48 of part 10a, whichever it may be. Gripping portion 64 of the terminal 62 is thus properly crimped and cannot be spread apart thereby to defectively attach terminal 62 to the conductor 58 as the edges 32, 34 of part 10a will not permit the terminal portion 64 to spread, and the surface 36 being curved, urges the opposite tabs 63, 65 of the terminal portion 64 inwardly toward each other. Specifically, the force indicated by the arrow 46 can be applied to the anvil surface 44 by means of a hammer; however, it is obvious that other means for driving the part 10b toward part 10a will be equally satisfactory. When part 10b is driven toward part 10a, for the first time after part 10a has been secured to the block of wood 52, the leg portions 40, 42 will simultaneously form their own holes 68, 70 in the block of wood 52. Thereafter, only a force sufficient to crimp the terminal 62 need be applied to part 10b as the holes 68, 70 formed theretofore will suffice to allow leg portions 40, 42 of part 10b to penetrate the wood 52 sufficient distance to allow the surface 36 of part 10b to approach the surface 47 or 48 of part 10a sufficiently to crimp terminal 62.

It can be readily seen that the tool of this invention can be relatively inexpensively made and simply operated. Also, by specifying the proper distance between edges 32, 30 and proper curvature of edge 36, the tool will crimp terminals such as indicated by the reference numeral 62 in the proper manner thereby insuring a permanent attachment of terminal 62 to a conductor 58.

While there have been described and illustrated above the principles of this invention in connection with specific apparatus, it is to be clearly understood that this de-

scription is made only by way of example and not as a limitation to the scope of this invention.

What is claimed is:

1. A terminal crimping hand tool comprising a pair of identical metal plates each having a rectangular shape, opposite ends, a longitudinal axis and a pair of openings therein, said openings being generally rectangular and coaxial with said longitudinal axis, said openings being longitudinally spaced-apart from each other and the boundaries of said plate and in end to end relationship with each other, one of said ends of each of said plates having a notch formed therein, said notch being bounded by two side edges which are parallel and spaced-apart from each other and from the longitudinal edges of said plate and a third curved bottom edge extending between said two side edges thereby providing each of said plates with two parallel leg portions at said one end, said leg portions of each of said plates being adapted to fit into said openings of the other of said plates, each of said plates having an anvil surface at the other of said ends.

2. The tool of claim 1 wherein each of said plates has a second pair of openings therein, one of said plates being secured to a block of soft wood by fastening means in said second pair of openings, and the other of said plates being positioned generally perpendicular to said one plate with said leg portions thereof inserted in said first-named openings of said other plate whereby solderless terminals can be crimped between said curved edge of said other plate and a surface of said one plate.

3. The tool of claim 1 wherein one of said plates is positioned generally perpendicular to the other of said plates with said leg portions thereof inserted in said openings of said other plate whereby solderless terminals can be crimped between said curved edge of said other plate and a surface of said one plate.

4. The tool of claim 1 further comprising line indicia on one surface of each of said plates parallel to said axis and the longitudinal edges of said plates, said indicia being spaced from one of said longitudinal edges a distance equal to the crimped portion of a terminal thereby providing a gauge for indicating the correct distance a wire should be stripped prior to having a terminal secured thereon.

5. A terminal crimping tool comprising a pair of metal plates, one plate of said pair having a pair of generally rectangular spaced-apart openings therein aligned in end-to-end relation, one of the ends of the other of said plates having a notch formed therewith thereby forming a pair of generally parallel leg portions at said one end, said leg portions being adapted to fit into said openings, said other plate having an anvil surface at the other end, whereby solderless terminals can be crimped between said plates.

6. The tool of claim 5 wherein said one plate has means for securing the same to a support.

7. A terminal crimping tool comprising a first plate having a pair of spaced-apart openings therein, a second plate having opposite ends, a pair of leg portions and a curved edge extending therebetween at one end, and an anvil surface at the other end, said leg portions being adapted to fit into said openings thereby to crimp terminals between said curved edge and said first plate.

8. A terminal crimping tool comprising a pair of plates each having a pair of spaced-apart openings therein aligned in end-to-end relation and a notch formed in one of said ends thereby forming a pair of leg portions, said leg portions of each one of said pair of plates being adapted to fit into said openings of the other of said pair, and means for driving said leg portions into the respective openings, whereby solderless terminals can be crimped between said plates.

9. A terminal crimping tool comprising a pair of identical plates each having a pair of spaced-apart openings therein, means for securing said plate to a support, and

at one end of said plate a pair of leg portions and a curved edge extending therebetween, said leg portions of each of said plates being adapted to fit into said openings of the other of said plates, and means for driving said leg portions into the respective openings, thereby to crimp terminals between said curved edge of said one plate and the surface of said other plate.
